BY
Lawrence D. Pearson ATTORNEY.

UNITED STATES PATENT OFFICE.

ALBERT A. LAFAYETTE, OF LAWRENCE, MASSACHUSETTS.

LUG-STRAP HOLDER.

1,376,148.

Specification of Letters Patent. Patented Apr. 26, 1921.

Application filed February 12, 1921. Serial No. 444,477.

To all whom it may concern:

Be it known that I, ALBERT A. LAFAYETTE, a citizen of the United States, residing at Lawrence, in the county of Essex and State 5 of Massachusetts, have invented certain new and useful Improvements in Lug-Strap Holders, of which the following is a specification.

This invention relates to supports for 10 what is known as lug straps on power looms. Such lug straps give motion to the picker stick and must be supported, preferably in adjusted relation thereto.

Lug straps are now generally supported 15 by what is known as power straps, which consist of a strip of leather attached to the picker stick by means of a screw.

The constant pounding of a picker stick makes it break frequently and the screw of 20 the power strap weakens it.

The purpose of my device is to provide a holder for a lug strap which will strengthen instead of weaken the picker stick, which can be adjusted with great nicety, and 25 which clasps the picker stick with a soft, firm grip, thus strengthening the picker stick and preventing the lug strap holder from being shaken out of position.

In the drawings, Figure 1 is a side elevation of my holder, including the lug strap support in place on a picker stick, the lug strap being shown partly broken away. Fig. 2 is an elevation from the right of Fig. 1, the lug strap being shown partly broken 30 away. Fig. 3 is a sectional view of the clamping device from the left of line 3—3 of Fig. 1. Fig. 4 is a detail elevation showing another form of clamping nose and altering means. Fig. 5 is an elevation similar to Fig. 2 showing another form of lug 35 strap support. Fig. 6 is a perspective view of another form of lug strap support. Fig. 7 is a sectional elevation showing a slight modification of the connecting member and 40 nut.

In the drawings, A represents a picker stick of the usual construction and B represents a lug strap, also of the usual construction.

C represents a support for the lug strap B which may be made of thick leather or fiber or other suitable material. It consists of a shank or back-bone 4 which is the same width as the picker stick and extends outward at the top in the form of arms 10, and at another point a distance below 10

equal to the height of the lug strap in the form of arms 11, so that the lug strap B will be confined between the top arms 10 and the middle arms 11. 60

As shown, there is a tail 12 or bottom extension with bottom arms 13 and a reinforcing plate 14 of such size as to permit my clamping member F to support it in a manner to be described. 65

My clamping member F is a U-shaped metal yoke comprising parallel arms 20 spaced apart a distance to readily embrace the picker stick and connected at what might be called the front by a connecting 70 member 27 through which is a hole 28 for the passage of a screw 23 fixed to a bow spring 21 shown clearly in Fig. 1.

A nut 22, preferably of the form and of such size as to fit in between arms 20, 20, 75 preferably has projections at the top and bottom 29 whereby it can slide back and forth between arms 20, 20, but cannot possibly turn.

This nut 22 is threaded to receive the 80 screw 23, and it is obvious that by removing the spring 21 with its screw 23 and nut 22, the distance from spring 21 to the nut 22 can be altered at will, and when put back in position it is impossible for the nut to 85 unscrew or for the relation between the bow spring 21 and connecting member 27 to change. Thereby an elastic connection between the clamp F and picker stick A can be maintained at the front. 90

Near the free end of each arm 20 is an angular slot 24 which has an open mouth at the top and extends down and out at 25, the end of 25 being formed on a proper curve to receive a pivot ear 31 of a clamping 95 nose 32. As shown in Fig. 1, this clamping nose 32 is provided with a suitable fixed handle 33, and the pivot ears 31 preferably have heads 26 to hold the free ends of arms 20 together when the device is in position. 100

To attach clamp F and put the spring 21 in position, it is slipped over the picker stick A in the desired position, arms 20, 20 passing by the tail 12 of lug strap support C below arms 11 and above arms 13. The 105 clamping nose pointing away from the picker stick is now pushed down so that its ears 31 will enter the mouth of the angular slot 24, then, by means of handle means 33, it is turned over and out so that the ears 110 pass into the part 25 of the slot, and the nose bears against reinforcing plate 14 on

tail 12 of support C. The motion is continued until the handle 33 comes almost to the picker stick, the nose 32 being in dead center relation between ears 31 and the 5 picker stick.

As shown in Fig. 4, I may use a clamping nose 50 with suitable ears 51, but instead of a permanent handle, I may have in place thereof a hole 52 to receive a handle 53 10 which can be inserted in 52 to turn the nose into position and then can be removed.

In place of the lug strap support C, I can use a stirrup arrangement shown at H in Fig. 5, having the lower part 12 and 13 15 similar to C, but the upper part made with parallel arms 41 and 42 connected at the top by a bar 40. In this case, the lug strap B passes between 41 and the picker stick and 42, and the picker stick is being held down 20 by bar 40 and up by the body 43.

Another form of lug strap support is shown in Fig. 6 consisting of a continuous strip of leather K having a middle portion 60 and two sets of projecting arms 61, 61, 25 two tails 12, 12 and two sets of end or bottom arms 13, 13, which can be brought together as shown to form a tail, so that the arms 20, 20 can pass between 61, 61 and 13, 13, thereby holding the device in place while 30 the loop 60 extends upward in such manner that the lug strap B can pass through it.

In Fig. 7, I show a slight modification in which the spring 21 has a somewhat shorter screw 71 which enters into a threaded hole 72 in a nut 70, which may be slightly thicker than 22, but does not pass therethrough. In this case the connecting member 27 need not have a screw passage 58.

It will be observed that the ends of bow 40 spring 21 which bear against the picker stick A may be rounded or more or less flattened, so that they neither bite into the wood nor form a sharp angle which would tend to weaken the picker stick.

45 I prefer also to make the lug strap support, or at any rate the supporting tail thereof shown at 12, of some compressible material like leather, whereby it coöperates with the bow spring and the clamping nose. 50 The whole holder is firmly but resiliently held on the picker stick.

I claim:

1. The combination in a lug strap holder of a support for the lug strap which extends 55 along the back of the picker stick and has a compressible tail; with a U-shaped metal yoke having a connecting member with a screw passage therethrough, and parallel arms which embrace the picker stick and the 60 tail of said support, each of said arms hav-

ing corresponding open mouthed angular slots near its free end; a bow spring between said arms, the connecting member and the picker stick which carries a fixed screw which projects through said screw passage; 65 a nut for said fixed screw which fits between said arms; a removable clamping nose with pivot ears which fit in said angular slots; and means to turn said nose on said ears as pivots so as to compress said tail. 70

2. The combination in a lug strap holder of a support for the lug strap which extends along the back of the picker stick and has a tail; with a U-shaped metal yoke having two parallel arms which embrace the picker 75 stick and the tail of said support, each of said arms having corresponding open mouthed angular slots near its free end, and a connecting member having a screw passage therethrough; a bow spring between said arms, the connecting member and the picker stick which carries a fixed screw projecting through said screw passage; a nut for said fixed screw which fits between said arms; a removable clamping nose with headed pivot 85 ears which fit in said angular slots; and removable means to turn said nose on said ears as pivots. 80

3. The combination in a lug strap holder of a support for the lug strap which extends 90 along the back of the picker stick and has a tail; with a U-shaped metal yoke having a connecting member with a screw passage therethrough, and parallel arms which embrace the picker stick and the tail of said support, each of said arms having corresponding open mouthed angular slots near its free end; a bow spring between said arms, the connecting member and the picker stick which carries a fixed screw which projects 100 through said screw passage; a nut for said fixed screw which fits between said arms; a removable clamping nose with pivot ears which fit in said angular slots; and means to turn said nose on said ears as pivots. 105

4. The combination in a lug strap holder of a support for the lug strap; with a U-shaped metal yoke having a connecting member, and parallel arms which embrace the picker stick and said support, each of 110 said arms having near its free end an open mouthed angular slot; a bow spring between said arms, the connecting member and the picker stick which carries a fixed screw; a nut for said fixed screw which fits between said 115 arms; a removable clamping nose with pivot ears which fit in said angular slot; and means to turn said nose on said ears as pivots.

ALBERT A. LAFAYETTE.
